UNITED STATES PATENT OFFICE.

KENNETH C. HURLEBUT, OF MONROE, WISCONSIN, ASSIGNEE OF ONE-HALF TO WILSON
G. BEAR, OF MONROE, WISCONSIN.

CHAIR ATTACHMENT.

1,056,337.

Specification of Letters Patent. Patented Mar. 18, 1913.

Application filed May 1, 1912. Serial No. 694,341.

To all whom it may concern:

Be it known that I, KENNETH C. HURLEBUT, a citizen of the United States, residing at Monroe, in the county of Greene, State of Wisconsin, have invented certain new and useful Improvements in Chair Attachments; and I do hereby declare the following to be a full, clear, and exact description of the invention, such as will enable others skilled in the art to which it appertains to make and use the same.

This invention relates to what I have termed "baby entertainers"—that is, a device intended for attachment to a child's chair, whereby the playthings may be kept at all times within easy reach of the child while he sits in the chair, thus keeping him amused without the attention of the mother or nurse.

20 The object of the invention resides in the provision of a chair attachment of the character referred to which may be easily applied to a chair, and which further includes a retaining or holding device for the playthings which will permit of the latter being moved by the child within the radius of his reach, but which will automatically return the playthings to a given position on the attachment when said playthings have been 25 released from the grasp of the child.

With the above and other objects in view, the invention consists in the details of construction and in the arrangement and combination of parts to be hereinafter more fully 30 described and particularly pointed out in the appended claim.

In describing the invention in detail, reference will be had to the accompanying drawings wherein like characters of reference 40 denote corresponding parts in the several views, and in which—

Figure 1 is a plan view of the attachment, Fig. 2, an end view of same, Fig. 3, a front view of the attachment, Fig. 4, a section on the line 4—4 of Fig. 1, Fig. 5, a fragmental detail perspective view of one of the spring operated winding drums employed in the attachment, and Fig. 6, a detail perspective view of one of the sections of the casing of 50 the winding drum.

Referring to the drawings the attachment is shown as comprising a playing board A adapted to be attached to a child's high chair so as to constitute what is commonly known 55 as the table of the chair. This board A is

provided with a predetermined playing area defined by longitudinal ribs 10 and transverse ribs 11 suitably secured to the board and rising above the upper face thereof. The board A is provided outwardly of one 60 of the transverse ribs 11 with a plurality of transversely aligned openings 12. Depending from the lower side of the board A is a bracket 13 disposed in transverse alinement with the openings 12. An angle rod 14 has 65 the free end of one of its arms secured in a suitable manner to the lower side of the board A while the other arm of said rod extends transversely of the board beneath the openings 12 and has its free end supported 70 in the bracket 13. Mounted upon the arm of the rod 14 which has its free end supported by the bracket 13 is a plurality of spring drums B corresponding in number to the openings 12. Adapted to be wound and un- 75 wound upon and from each of the drums B is a flexible connection 16 which extends through the adjacent opening 12 and has secured in a suitable manner to its free end a figure, toy or other device adapted to 80 afford amusement for a child.

Each of the drums B includes a casing formed of a pair of interlocking sections 17 and 18 which confine therein a reel member 19 rotatably mounted upon the rod 14. This 85 reel member 19 is formed of a disk 20 rotatably mounted on the rod 14 and having a peripheral flange 21 disposed at right angles to the disk. Mounted upon the peripheral flange 21 is a plurality of U-shaped 90 members 22 the arms of which form retaining fingers for the flexible connection 16 as the latter is wound upon or unwound from the flange 20. The reel member 19 has secured thereto one end of a spiral spring 23, 95 while the other end of said spring is anchored to an inwardly directed extension 24 of the casing section 18. The casing section 17 is provided with an opening 25 through which the connection 16 passes. It will be 100 noted that as the connection 16 passes through the adjacent opening 12 the casing sections 17 and 18 will be held against rotation during the unwinding of the connection 16 from the reel member 19 and that 105 such unwinding will energize the spring 23 so that when the unwinding force is released from the connection 16 said spring will rotate the reel member 19 to wind the connection 16 thereon. The disk 20 has 110

- struck therefrom a plurality of tongues 26 which are bent outwardly so as to form additional guide fingers operating in conjunction with the arms of the U-shaped members 5 22. The rod 14 and drums B are protected by a shield 27 having a U-shaped cross section and secured to the lower side of the board A in inclosing relation to said rod and drums.
- 16 From the construction previously described, it will be apparent that the figures or toys secured to the connection 16 may be moved by the child to the space disposed between the ribs 10 and 11. As soon as the 15 child releases a given toy or figure from its grasp or throws same off of the board A the connection attached thereto will be automatically wound upon the reel member of a given drum so as to return the toy or figure 20 to a position upon the upper side of the board A adjacent an opening 12 where it may be again readily grasped by the child.
- 25 As the possibility of the playthings of the child being thrown upon the floor is obviated it will be obvious that such play-

things are maintained in a highly sanitary condition.

What is claimed is:

The combination of a playing board having a defined playing surface on its upper 30 side provided with a plurality of openings disposed outwardly of said playing surface, a bracket depending from the lower side of said board, an angle rod having the free end of one arm secured to the lower side of 35 the board and the free end of its other arm supported in said bracket, a plurality of spring drums mounted on said rod, a plurality of flexible connections extending through said openings respectively and having corresponding ends secured to respective drums, and an amusement object secured to the other end of each of said connections.

In testimony whereof, I affix my signature, in presence of two witnesses.

KENNETH C. HURLBUT.
